UNITED STATES PATENT OFFICE.

CHARLES R. DRAKE AND JOHN HEBERLING, OF ROCHESTER, NEW YORK, ASSIGNEES
TO THE LINE-A-TIME MFG. CO. INC., OF ROCHESTER, NEW YORK, A CORPORATION
OF NEW YORK.

COPYHOLDER.

Application filed April 2, 1927. Serial No. 180,484.

Our present invention relates to copy holders and particularly to copy holders of the kind used in connection with and for transcribing upon typewriters wherein the copy holding means is disposed at the rear of the typewriter and forwardly extending bracing and operating means project at the side of the machine. Such copy holders embody either a stationary copy plate and a relatively movable line indicator which follows down the copy or a movable copying plate associated with a fixed line indicator. In either case the relative movement of the elements is effected with a step-by-step motion through suitable actuating mechanism. Our invention has for its object to improve this actuating mechanism. The improvements are directed in part toward providing means the regulation of which affords the operator greater or less mechanical advantage in operating the copy holder; toward providing adjustments whereby the operating mechanism is made convenient to the touch of the operator under different conditions and in different positions of the copy holder and toward provisions whereby the actuating mechanism in general is made to work more smoothly and without shock.

To these and other ends the invention resides in certain improvements and combinations of parts, all as will be hereinafter more fully described, the novel features being pointed out in the claims at the end of the specification.

In the drawings:

Figure 1 is a front elevation taken in section through the side arm of a copy holder constructed in accordance with and illustrating one embodiment of my invention;

Figure 2 is a top plan view in horizontal section through the supporting frame on the line 2—2 of Figure 1;

Figure 3 is a side view;

Figure 4 is an enlarged fragmentary view in horizontal section through the upright frame in the same plane as Figure 2 showing the folding arrangements of the frame and side arm;

Figure 5 is a detailed rear view of the universal joint between the operating lever and the actuating lever;

Figure 6 is an enlarged fragmentary view partly in section of certain controlling means for the actuating lever;

Figure 7 is a side view of said mechanism taken in section on the line 7—7 of Figure 6;

Figure 8 is an enlarged detailed perspective view of an element of the universal joint between the operating and actuating levers;

Figure 9 is an enlarged fragmentary perspective view of one end of the operating lever;

Figure 10 is a similar view of the cooperating end of the actuating lever, both levers in Figures 9 and 10 being shown in their assembled relationship;

Figure 11 is a detailed fragmentary perspective of one element of a joint in the actuating lever;

Figure 12 is an enlarged section through the operating lever on the line 12—12 of Figure 3;

Figure 13 is a top plan view of the operating lever and a fragmentary view of the side arm showing the position of the finger key different from that shown in Figure 2;

Figure 14 is a section on the line 14—14 of Figure 6; and

Figure 15 is a section on the line 15—15 of Figure 6.

Similar reference numerals throughout the several views indicate the same parts.

We have illustrated our invention in the present instance and will describe it as applied to the familiar type of copy holder, embodying the stationary line indicator and a movable copy plate. Referring more particularly to Figures 1 and 3, 1 indicates the copy plate having a paper clip or clasp 2 at the top thereof and movable vertically upon guide rods 3 on an upright supporting frame 4. The supporting frame, in the present instance, consists of a plate embossed rearwardly at 5 and having forwardly extending flanges 6 at its edges. It is secured at the bottom to a heavier reenforcing base plate 7 while the flange at the top forms a sliding bearing for a lifting rod 8 carried on the back of the copy plate. A lifting clutch 9 carried by a reciprocating clutch rod 10 engages the rod 8 above the frame while an independently supported holding clutch 11 engages the rod 8 below the frame. The clutch 9, as the clutch rod 10 is raised, raises the copy plate and while it is returning to initial position the clutch 11 maintains the plate against retrograde movement so that a step-by-step upward advance of the copy plate

past a stationary line indicator 12 disposed across its face and suitably supported by the frame 4 is effected. When the clutch rod 10 is abnormally depressed or lowered it releases both clutches and the plate falls to a lowermost position. It is shown in a partially raised position in the figures. The foregoing mechanism is well known in the prior art and our present invention is concerned 5 with it only in a general way for which reason the parts have been illustrated largely by dotted lines. It is the actuating mechanism for this clutch mechanism that our present invention deals with.

15 The frame and copy plate are held erect at the rear of a typewriter by a forwardly extending side arm 13 that lies at the side of the typewriter. Through a yoke 14 at its rear end it is pivoted at 15 to a yoke 16 20 (Fig. 1) projecting from the side of the main frame 4 adjacent to the base plate 7. To reduce the bulk of the copy holder for shipment or storage the side arm may, by this means, be folded across the face of the main 25 frame and copy plate as shown in Figure 4. Pivoted to the side arm at 17 is an operating lever 18 the forward end of which carries a handle or finger key 19 that projects for accessibility and convenience to the operator 30 adjacent to the key board of the typewriter. The particular construction of this finger key will be later referred to.

The rear end of the operating lever 18 is 35 operatively connected to the outer end of a relatively angularly disposed actuating lever 20 to which the lower end of the clutch rod 10 is pivoted at 21. This actuating lever is a lever of the second order being pivoted to the main supporting frame plate 4 at 22. It will 40 therefore be seen that by depressing the operating lever 18 the copy plate 1 will be raised one step through a consequent raising of the actuating lever 20 and the clutch rod 10. The degree of raising movement is limited by a 45 suitable stop device 23 on the main frame controlled by a thumb nut 24 and which the actuating lever 20 engages. After the depression of the operating lever all of the parts including the clutch 9, rod 10, actuating 50 lever 20 and operating lever 18 return to normal position through the influence of a spring 25 acting upon the actuating rod. Lifting or upward pressure on the operating lever 18 55 reverses the actuating lever 20 and pulls downwardly on the clutch rod 10 releasing both clutches and permitting the copy plate to fall. A spring 26 on the holding clutch 11 is superior in its action to the spring 25 so that the clutch is tripped only by positive 60 downward pressure.

Referring now more particularly to Figures 3, 12 and 13, the finger key or handle 19 is tubular to slidably receive telescopically the end of the operating rod 18 which may be 65 graduated at 27 to indicate various stop po-

sitions in the relative adjustment. The key is secured in these various positions by the tightening of a bolt 28 passing through ears 29 on the under side of the key whereby it is clamped to the lever. This arrangement is 70 principally for the purpose of lengthening or shortening the lever to bring it where it belongs beside the key board of the typewriter after the copy plate has been disposed at the desired distance behind the machine. 75 It is also useful, however, in regulating the "touch" in the operation of the copy holder, that is, regulating the necessary pressure of the hand on the key 19 to raise the copy to the desired distance as the leverage is increased or decreased according to the position of the key.

In either case this change in leverage or in mechanical advantage to the operator occurs. To compensate for it and as a part of 80 the mechanism for regulating the "touch" we make the returning spring 25 for the actuating lever adjustable, and in doing so arrange an improved means for limiting the returning movement and absorbing the shock 90 thereof.

As shown in Figure 14 the pivot screw 22 of the actuating lever 20 is a shouldered screw having a lock nut 30 on the rear side of the frame plate 4. Turning on this lever is a 95 stop plate 31 having a segmental arm 32 (Figure 6). The lower end of the spring 25 is connected at 33 to a lever 34 pivoted to the stop plate at 35. This lever is guided in a slotted flange 35^a on the arm 32 and provided 100 with a locking projection 36 cooperating with a plurality of stop openings 37 in the stop plate arm. Through the adjustment of this lever the tension of the spring 25 is regulated. The stop plate itself is prevented from being 105 turned on its pivot by this spring in a manner later described.

The stop plate 31 has the general form of a bell crank lever and the upper arm thereof is provided with a preferably rubber covered 110 limiting stop pin 38 which halts the downward movement of the actuating lever 20 and defines its normal position. To take the shock of the impact of the lever with the pin after an actuation the other arm 39 of the bell crank stop plate is provided with a spring plunger 40. This shock absorbing device in the present instance consists of a headed screw 41 passing through an opening in the side flange 6 of the supporting frame plate 115 4 and threaded into ears 42 on the stop plate arm 39. A compression spring 43 surrounds the screw between the arm and the frame flange while the threads of the screw permit the compression of the spring to be regulated 120 from the exterior to vary the shock absorbing action. It is this shock absorbing plunger, or, more particularly, in the present instance, the head of the screw 41 that stops 125 upward swinging movement of the stop plate 130

31 under the action of the spring 25 which it is utilized to adjust.

Referring now to Figures 2 to 5 and 8 to 11 it is obvious that inasmuch as the operating lever 18 and the actuating lever 20 turn in different planes, some provision must be made to compensate for the divergence of the arcs that they describe. For this purpose we have devised a very simple and effective universal joint between the two levers. The cooperating extremity of the operating lever 18 is provided with a longitudinally projecting pivot 44 and the companion end of the actuating lever 20 is provided with a similar pivot 45. These cross each other as shown in Figures 9 and 10 and occupy relatively angular upper and lower bearings 46 and 47 in a bearing block 48. Each pivot both turns and slides in its bearing in the block which floats between the two levers and adapts itself to the arcs of both. Each lever prevents its disengagement from the other once their pivots are in place which makes assembling a simple matter without the use of fastenings.

25 The folding of the side arm 13 and its operating lever also necessitates a provision for folding movement with respect to the connection between the two levers. For this purpose we, in the present instance, provide a knee joint in the actuating lever 20 the pivot or pintle of which shown at 49 is aligned with the pivot 15 between the side arm 13 and the main frame 4. The joint is constructed in a manner clearly shown in Figures 10 and 11, 30 the cooperating knuckles 50 and 51 being angled off at their ends to permit folding of the actuating lever at this point only in a forward direction and locking against movement in the opposite direction that would result 35 in the universal joint coming apart.

40 We claim as our invention:

1. In a copyholder, the combination with a supporting frame and a copy-plate and line indicator mounted thereon for relative movement, of mechanism for imparting a step-by-step movement to one of said last mentioned elements embodying an actuating lever and an operating lever, a spring for returning the actuating lever after each operation, means 45 for varying the leverage of one of said levers and means for varying the tension of the spring accordingly.

2. In a copyholder, the combination with a supporting frame and a copy-plate and line indicator mounted thereon for relative movement, of mechanism for imparting a step-by-step movement to one of said last mentioned elements embodying an actuating lever and an operating lever, a spring for returning the actuating lever after each operation, an adjustable finger key on the operating lever for varying its leverage and means for varying the tension of the spring accordingly.

3. In a copyholder, the combination with a 65 supporting frame and a copy-plate and line

indicator mounted thereon for relative movement, of mechanism for imparting a step-by-step movement to one of said last mentioned elements embodying an actuating lever and an operating lever, a spring for returning the actuating lever after each operation, a tubular finger key adjustable on the operating lever to vary its leverage and means for varying the tension of the spring accordingly.

4. In a copyholder, the combination with a supporting frame and a copy-plate and line indicator mounted thereon for relative movement, of mechanism for imparting a step-by-step movement to one of said last mentioned elements embodying an actuating lever and an operating lever, a spring for returning the actuating lever after each operation, means for varying the leverage of one of said levers and means for varying the tension of the spring accordingly, embodying a lever connected to the spring and a relatively fixed stop plate with which the lever cooperates.

5. In a copyholder, the combination with a supporting frame and a copy-plate and line indicator mounted thereon for relative movement, of mechanism for imparting a step-by-step movement to one of said last mentioned elements embodying an actuating lever and an operating lever, a spring for returning the actuating lever after each operation, means for varying the leverage of one of said levers and means for varying the tension of the spring accordingly, embodying a stop plate mounted on the pivot of the actuating lever, a lever pivoted to the stop plate and connected to the spring and interlocking with the stop plate in different positions, and a limiting stop on the stop plate for halting the return movement of the actuating lever.

6. In a copyholder, the combination with a supporting frame and a copy-plate and line indicator mounted thereon for relative movement, of mechanism for imparting a step-by-step movement to one of said last mentioned elements embodying an actuating lever and an operating lever, a spring for returning the actuating lever after each operation, means for varying the leverage of one of said levers and means for varying the tension of the spring accordingly, embodying a pivoted stop plate, a lever pivoted to the stop plate and connected to the spring and interlocking with the stop plate in different positions, a limiting stop on the stop plate for halting the return movement of the actuating lever, and a shock absorber cooperating with the stop plate to resist movement imparted to the latter by the actuating lever through the limiting stop.

7. In a copyholder, the combination with a supporting frame and a copy-plate and line indicator mounted thereon for relative movement, of mechanism for imparting a

step-by-step movement to one of said last mentioned elements embodying an actuating lever, a spring for returning the latter, a stop plate having a limiting stop for halting the return movement of the actuating lever, and a device mounted on the stop plate for varying the tension of the spring.

8. In a copyholder, the combination with a supporting frame and a copy-plate and line indicator mounted thereon for relative movement, of mechanism for imparting a step-by-step movement to one of said last mentioned elements embodying an actuating lever, a spring for returning the latter, a pivoted stop plate having a limiting stop thereon for halting return movement of the actuating lever, and a shock absorber cooperating with the stop plate to resist movement imparted to the latter by the actuating lever 20 through the limiting stop.

9. In a copyholder, the combination with a supporting frame and a copy-plate and line indicator mounted thereon for relative movement, of mechanism for imparting a step-by-step movement to one of said last mentioned elements embodying an actuating lever, a spring for returning the latter, a bell crank pivoted on the axis of the actuating lever and having a limiting stop on one arm thereof for halting return movement of the actuating lever and a shock absorber cooperating with the other arm of the bell crank to resist movement imparted to the latter by the actuating lever through the limiting stop.

35 10. In a copyholder, the combination with a supporting frame having a side flange and a copy-plate and line indicator mounted thereon for relative movement, of mechanism for imparting a step-by-step movement to one of said last mentioned elements embodying an actuating lever, a spring for returning the latter, a bell crank lever pivoted on the frame and having a limiting stop on one arm thereof for halting return movement of the actuating lever, and a shock absorber cooperating with the other arm of the bell crank to resist movement imparted to the latter by the actuating lever through the limiting stop, said shock absorber embodying a spring plunger 50 extending through the flange of the supporting frame and having a spring tensioning device accessible for adjustment from the opposite side of the flange.

55 11. In a copyholder, the combination with an upright supporting frame, a side arm brace pivoted thereto at one side to fold from an extended operative position to a folded position across the face of the frame, and a copy-plate and a line indicator mounted on the frame for relative movement, of mechanism for imparting a step-by-step movement to one of said last mentioned elements embodying an actuating lever extending across the face of the frame and having a knee-joint

aligned with the pivot of the frame and side 65 arm, an operating lever pivoted on the side arm, and a universal joint connecting the two levers between the pivot of the operating lever and the knee-joint of the actuating lever.

12. In a copyholder, the combination with 70 a supporting frame and a copy-plate and line indicator mounted thereon for relative movement, of mechanism for imparting a step-by-step movement to one of said last mentioned elements embodying an actuating lever and 75 an operating lever, arranged angularly to each other and having pivot extensions at their ends, and a bearing block having relatively angular bearings arranged in different planes to slidably and rotatably receive 80 the respective pivot extensions of the two levers and constitute a universal joint connecting them for movement.

13. In a copyholder, the combination with 85 a supporting frame, and a copy-plate and line indicator mounted thereon for relative movement, of mechanism for imparting a step by step movement to one of said last-mentioned elements including an actuating lever, resilient means for returning the actuating lever after each operation, a limiting stop for 90 said lever, and cushioning means supporting said limiting stop for absorbing the impact of said lever with said stop.

14. In a copyholder, the combination with 95 a supporting frame, and a copy-plate and line indicator mounted thereon for relative movement, of mechanism for imparting a step by step movement to one of said last-mentioned elements including an actuating lever, resilient 100 means for returning the actuating lever after each operation, a limiting stop for said lever, a stop plate mounted for limited pivotal movement carrying said limiting stop, and resilient means normally retaining said stop 105 plate at one limit of its movement, said stop plate and last-mentioned means cooperating to absorb the impact of the lever with said limiting stop.

15. In a copyholder, the combination with 110 a supporting frame, and a copy-plate and line indicator mounted thereon for relative movement, of mechanism for imparting a step by step movement to one of said last-mentioned elements including an actuating lever, a 115 spring for returning the actuating lever after each operation, a limiting stop for said lever, a stop plate having limited pivotal movement carrying said limiting stop, resilient means 120 for normally retaining said stop plate at one limit of movement, said plate and resilient means cooperating to absorb the impact of said lever with said stop, and an adjustable anchor for said spring on said stop plate operable to vary the tension thereof.

CHARLES R. DRAKE.
JOHN HEBERLING.
